UNITED STATES PATENT OFFICE

2,589,992

LIQUID DISPENSING AND FEEDING APPARATUS

Walter F. Cohrs, Glencoe, Minn.

Application May 11, 1950, Serial No. 161,367

4 Claims. (Cl. 210—29)

1

My invention relates generally to liquid dispensing apparatus and more specifically to apparatus for automatically dispensing liquids such as chemicals or the like in relatively small quantities, and delivering the same to its point of use.

More particularly, my invention relates to mechanism for adding small quantities of chemicals, such as acid, to water for the prevention of scale or the like in a water container, as for instance in the cooling systems of liquid-cooled stationary engines.

An important object of my invention is the provision of apparatus which will automatically dispense predetermined quantities of liquid at a uniform predetermined rate.

Another object of my invention is the provision of apparatus as set forth in which the rate of feed of the liquid may be varied.

A still further object of my invention is the provision of a dispenser of the above type which is relatively simple and inexpensive to produce and which is efficient in operation and durable in use.

Other highly important objects and advantages of my invention will become from the following detailed description, appended claims, and attached drawings.

Referring to the drawings, wherein like characters indicate like parts throughout the several views:

Fig. 1 is a view in side elevation of my novel dispensing and feeding mechanism;

Fig. 2 is a view in plan;

Fig. 3 is a vertical section taken substantially on the line 3—3 of Fig. 2; and

Fig. 4 is an enlarged fragmentary detail partly in elevation and partly in section of a portion of the feeding mechanism of my invention.

In the cooling of liquid stationary engines of the water cooled internal combustion type, it is often necessary to treat the coolant with certain chemicals, such as sulphuric acid or the like, in order to prevent scale from forming in the cooling system. For the purpose of adding the exact required amount of chemical, I provide a container for holding the chemical, which is liquid in form, and means for extracting the liquid from said container at a predetermined uniform rate and delivering the same to the cooling system. In the drawings, the numeral 1 indicates in its entirety a frame structure comprising a base 2 and a pair of laterally spaced side frame members 3 and 4. An upright bracket 5 is rigidly secured by nut-equipped

2

screws or the like 6 to the upper end portions of the frame members 3 and 4 and is provided with a shelf element 7 upon which is adapted to rest an inverted container 8. The container 8 is held in position by a holding strap or the like 9 secured to the upper end portion of the bracket 5 by nut-equipped bolts or the like 10.

The mouth of the container 8 is closed by a sealing ring or cap 11 having a central opening 12 which extends axially of the container 8 and into which is pressed the upper end of a depending open-ended tubular conduit 13. The conduit 13 extends downwardly through an opening 14 in the shelf 7 and overlies a funnel-like receiver 15 mounted in the base 2 and connected to a flexible tube or conduit 16 which may be assumed to lead to the cooling water supply source or to the cooling system of an engine. The liquid chemical for treating the water is indicated by X in Fig. 3. A plunger rod 17 is shown as projecting loosely upwardly through the conduit 13 into the interior of the container 8. It should be noted that when the container 8 is in its inverted position as shown, that the differential in air pressure between the inside of the container 8 and surrounding atmosphere maintains the liquid X in equilibrium therein. Upward movement of the plunger rod 17 to a predetermined extent causes some of the air within the container 8 to be displaced, thereby upsetting the equilibrium of the liquid X therein and permitting the liquid to flow downwardly through conduit 13 and into receiver 15 until equilibrium is restored. On the other hand, downward movement of the plunger rod 17 with respect to the container 8 increases the partial vacuum therein sufficiently to cause air to rise upwardly through the conduit 13 to the interior of the container 8 until equilibrium is again restored.

From the above it will be seen that the amount of movement of the plunger rod 17 determines the amount of the liquid X to be dispensed from the container. I have found that by controlling the length of axial movement of the plunger rod 17 that I can regulate dispensing of liquid X to a very exact degree.

I provide means for imparting reciprocatory movements to the plunger rod 17, said means including a rock arm 18 mounted at its intermediate portion on a horizontally disposed rock shaft 19 journaled at its opposite ends in the opposite side members 3 and 4. One end of the rock arm 18 is provided with an extension 20 which underlies the lower end of the plunger

rod 17 and is engageable therewith upon rocking movements to raise the same. The plunger rod 17 is preferably made from glass or metal impervious to chemical action of the liquid X, as is the extension 20, and is gravity-biased toward engagement with the extended portion 20. The opposite end of the rock arm 18 overlies and is adapted to be engaged by a cam 21 mounted fast on a rotary shaft 22 which is journalled in the opposite side frame members 3 and 4, and which is driven by an electric motor 23 to the shaft 24 of which is rigidly secured a pinion 25. Said pinion 25 has meshing engagement with a gear 26 mounted fast on an extended end portion of the shaft 22. As shown, the motor 23 is mounted on the base 2 by means of mounting screws or the like 27. A coil tension spring 28 is anchored at one end of the base 2 and at its other end to a down-turned flange 18' on the rock arm 18 intermediate the rock shaft 19 and the cam 21 whereby to exert yielding bias against the adjacent end of the rock arm 18 in the direction of the cam 21. The extent of rocking movements of the rock arm 18 is controlled by a stop element 29 mounted fast on a shaft 30 which is journalled in the opposite side frame members 3 and 4 between the shafts 19 and 22 and parallel thereto.

The stop element 29 is eccentric to the shaft 30 whereby rotation thereof will cause the stop element 29 to be moved upwardly or downwardly as desired. A control knob 31 is mounted fast on one end of the shaft 30 laterally outwardly of the side frame member 3 for manual control of the stop element 29. Suitable friction means not shown are employed to prevent accidental rotation of shaft 30.

Rotation of the shaft 22 causes the cam 21 to move into operative engagement with the adjacent end of the arm 18 whereby to impart rocking movements thereto and resultant reciprocating movement to the plunger rod 17. As heretofore described, the reciprocating movements of the plunger rod 17 will cause alternate escape of a predetermined quantity of liquid X downwardly through the conduit 13, and ingress of air therethrough to the interior of the container 8. By reason of the fact that the motor 23 runs at a constant speed, a uniform rate of flow of the liquid X from the container 8 is assured, said rate of flow being capable of variations by manual movement of the stop element 29 to raise or lower the quantity of fluid X desired.

My invention has been thoroughly tested and found to be completely satisfactory for the accomplishment of the objectives set forth; and while I have shown and described a commercial embodiment of my novel dispensing apparatus, it will be understood that the same is capable of modification without departure from the spirit and scope of the invention as defined in the claims.

What I claim is:

1. In a device of the class described, a frame structure, a liquid container, means mounting said container in an inverted position on said frame structure, an open-ended tubular dispensing conduit depending from the inverted container, a plunger rod extending loosely through said conduit for axial movements therethrough and having its upper end portion disposed within said container, the liquid in the container being normally retained in equilibrium by a differential in air pressure, movement of said plunger rod in an upward direction causing a pressure

rise within said container and a resultant flow of liquid therefrom until equilibrium is restored, movement of the plunger rod in the opposite direction causing a pressure drop within said container whereby air is drawn upwardly through said conduit to restore equilibrium, a rock arm journalled intermediate its ends in said frame structure, one end of said rock arm being engageable with the lower end of said plunger rod to impart raising and lowering movements thereto, a cam engageable with the opposite end of said rock arm to impart rocking movements thereto, and yielding means biasing said rock arm in the direction of the cam.

15. 2. The structure defined in claim 1 in further combination with manually operated means for controlling the extent of rocking movement of said arm.

3. In a device of the class described, a frame structure, a liquid container, means mounting said container in an inverted position on said frame structure, an open-ended tubular dispensing conduit depending from the inverted container, a plunger rod extending loosely through said conduit for axial movements therethrough and having its upper end portion disposed within said container, the liquid in the container being normally retained in equilibrium by a differential in air pressure, movement of said plunger rod in an upward direction causing a pressure rise within said container and a resultant flow of liquid therefrom until equilibrium is restored, movement of the plunger rod in the opposite direction causing a pressure drop within said container whereby air is drawn upwardly through said conduit to restore equilibrium, a rock arm journalled intermediate its ends in said frame structure, one end of said rock arm being engageable with the lower end of said plunger rod to impart raising and lowering movements thereto, a cam engageable with the opposite end of said rock arm to impart rocking movements thereto, yielding means biasing said rock arm in the direction of the cam, and means limiting rocking movements of said rock arm in one direction, said means comprising a manually adjustable stop element mounted on said frame and engageable with said rock arm intermediate the pivot axis thereof and said cam.

4. The structure defined in claim 3 in which the plunger rod engaging end portion of said rock arm underlies said plunger rod, and in which said plunger rod is gravity biased toward engagement therewith.

55. WALTER F. COHRS.
